UNITED STATES PATENT OFFICE.

WILLIAM S. NOYES, OF CHICAGO, ILLINOIS.

DESIGN FOR A SPROCKET-WHEEL AND CHAIN GUARD.

SPECIFICATION forming part of Design No. 26,900, dated April 13, 1897.

Application filed January 16, 1897. Serial No. 619,506. Term of patent 7 years.

To all whom it may concern:

Be it known that I, WILLIAM S. NOYES, a citizen of the United States, and a resident of Chicago, in the county of Cook and State of Illinois, have invented and produced a new and original Design for Sprocket-Wheel and Chain Guards or Shields for Bicycles, of which the following is a specification.

In the accompanying drawings a guard or shield of my design is fully illustrated.

Figure 1 is a front view of a guard or shield of my design; and Fig. 2 is a rear transverse section thereof, taken on the dotted line of Fig. 1.

A guard or shield of my design comprises, among its essential features, a marginal frame A, the edges of which are continuous and the space within which is occupied by open-work A', both said marginal frame and open-work being made as light as consistent with necessary strength. The edges of the marginal frame A being continuous the garments of the rider will not catch thereon, and the open-work within said marginal frame effectually prevents the garments of the rider from coming in contact with the sprocket-wheels and driving-chain of the bicycle and also serves to connect the opposite sides of the marginal frame between their ends, thereby bracing and strengthening said guard.

As shown in the drawings, the open-work A' forms a scroll, but it is obvious that the pattern of said open-work may be varied without departing from my invention. For instance, other forms of scroll might be substituted for the particular scroll shown, or said open-work might form a regular geometrical figure or might embody a monogram or a maker's name.

Holes or openings a a' are formed in the open-work A' to receive and accommodate the various parts and frame members of the bicycle which would interfere with adjusting said guard or shield to the bicycle. In a guard or shield of my design also the marginal frame A comprises a flange A², which extends laterally therefrom to cover the sprocket-wheels and driving-chain.

I claim—

The design for a sprocket-wheel and driving-chain guard or shield for bicycles, substantially as herein shown and described.

In testimony that I claim the foregoing as my invention I hereunto set my hand, this 15th day of December, 1896, in the presence of two witnesses.

WILLIAM S. NOYES.
